UNITED STATES PATENT OFFICE

2,665,127

TRUCK STABILIZER PACKAGE UNIT

Charles P. Leese, Chicago, Ill., assignor to Standard Car Truck Company, Chicago, Ill., a corporation of New Jersey

Application July 30, 1949, Serial No. 107,812

1 Claim. (Cl. 267—9)

1

My invention relates to a railway car truck stabilizer in the form of a pre-assembly of various springs and cooperating friction elements adapted to be installed in the truck as a unitary structure.

One of the objects of my invention is the provision of a self-contained stabilizer unit assembly for use in railway car trucks, the said unit assembly including load supporting springs and friction means for damping the movement of said springs.

Another object of my invention is the provision of a stabilizer unit, as above described, which is adapted for installation either as original equipment or as a conversion unit suitable for converting existing non-stabilized trucks into stabilized trucks by simply removing the load springs from the truck and inserting, in the place occupied by said springs, the applicant's improved unitary or package form of stabilizer.

A further object of my invention is the provision of an assembly of the foregoing type in which the damping action on the load springs of the truck is effected by friction means acting independently of the load springs, but which progressively increases the damping action in proportion to the compression of the load springs.

Other and further objects of my invention will become apparent from the following description considered in connection with the accompanying drawings in which:

Fig. 1 is a fragmentary elevational view of a railway car truck embodying the invention, the view being taken longitudinally of the truck.

Fig. 2 is a vertical cross-sectional view taken on line 2—2 of Fig. 1.

Fig. 3 is a top plan view of the invention.

Fig. 4 is a side elevational view thereof partly in section, the section being taken substantially on line 4—4 of Fig. 3.

Fig. 5 is a front elevational view partly in section, the section being taken substantially on line 5—5 of Fig. 3.

Referring to the drawings, particularly Figs. 1—5, the improved stabilizer unit is indicated generally by the numeral 10 and is shown as incorporated in the side frame of a railway truck. The truck frame is of generally conventional construction and includes a compression member 11, a tension member 12 and integral vertical columns 13. The vertical columns form with the members 11 and 12 a bolster window 14 with the tension member 12, in the specific form of frame shown being widened to provide a spring seat 15 of suitable width. The compression member 11

2

is provided with a brake hanger bracket shown at 16. The structure hereinabove described is conventional and may be varied as may be desired without affecting the principles of the present invention.

The present invention is concerned particularly with the railway car truck stabilizer package unit 10. The said unit is a self-contained assembly and may be installed in railway trucks, 10 such as hereinabove described, either as original equipment or as a replacement assembly for conventional load spring groups. The improved stabilizer unit 10 includes upper and lower spring plates 41 and 42 respectively, each provided with 15 retaining flanges 43 to prevent displacement of the double coiled load springs 44 disposed between the said plates. Secured to the lower plate 42 as by rivets 50 is a casing 45 having side walls 46 and end walls 47. The bottom 48 of the casing 45 is provided with integral laterally extending wings 49—49 which are perforated to accommodate the rivets 50. The bottom 48 of the casing is provided with two spaced bosses 51, each of which serves to locate and retain one end of a 20 stabilizer spring 52, two of such springs being provided. The side walls 46 of the casing 45 are slotted substantially medially thereof as at 53 to accommodate a pin 54. Welded to the inner faces of each of the end walls 47 of the casing 45 is a 25 wear plate 56.

Secured to the under side of the upper spring plate 41, as by rivets 57, is an intermediate wedge member 58 shaped in transverse cross-section substantially as shown in Fig. 5. The said intermediate wedge member 58 cooperates with the stabilizing springs to urge the friction wedges laterally against the wear plates 47—47. To this end central wedge member is provided with a depending V-shaped portion forming opposed 30 wedge surfaces 59. Integrally connected with the V-shaped portion 58 is a U-shaped portion or loop 61 which is located substantially in alignment with the vertical slots 53 in the side walls 46 and is adapted to receive the pin 54 which is 35 passed through the slots 53 and through the U-shaped portion 61 to retain the parts of the package unit in assembled relation. The U-shaped section 61 is disposed centrally of the intermediate wedge member 58, while the surfaces 40 of the V-shaped portion of wedge 58 extend substantially across the width of the interior of the casing 45.

Arranged on opposite sides of the intermediate floating wedge member 58 are friction wedges 62 45 shaped in cross-section substantially as shown in

Fig. 5. The said friction wedges each include a vertical wall 63 engageable with the exposed face of a wear plate 56, a top portion 64 from which depends a boss 66 aligned with a boss 51 of the casing 45 so as to locate and retain a stabilizer spring 52 therebetween, and an inclined wall 67 complementary to the wedge surface 59 of the wedge member 58. The inclined wall is slotted as at 68 to accommodate the U-shaped portion 61.

In the assembling of the stabilizer unit, the stabilizer springs 52 are partially compressed, so that the friction wedges 62—62 are continuously urged upwardly and are caused to bear against the wear plates 56—56 at the ends of the casing 45. The pressure of the vertical walls 63—63 of the friction wedges 62—62 against the wear plates 56—56 is determined by the angle of inclination of the cooperating wedge surfaces and also by the pressure of the stabilizer springs 52—52 against the friction wedges 62—62. It will be apparent that when a load is applied to the upper spring plate 41, as when a bolster is resting thereon, the load springs 44 are compressed and the central wedge member 58 is moved downwardly. This effects a corresponding movement of the friction wedges 62—62 and compresses the stabilizer springs 52—52 which, with each increment of compression, exert a progressively increasing force upwardly against the friction wedges 62—62, thereby progressively increasing the frictional resistance between the friction wedges 62—62 and the wear plates 56—56. Thus, in the event that a shock load is transmitted to the unit, resistance to downward movement of the load springs 44 is progressively increased with each increment of movement thereof. Correspondingly, with a decrease of the load on the unit, the frictional resistance between the friction wedges 62—62 and the wear plates 56—56 is progressively reduced with each increment of recoil movement.

The structure hereinabove described is pre-assembled as a package unit and is intended to be installed in the truck of a railway car in the manner shown in Figs. 1 and 2 of the drawings. When the stabilizer unit is installed in a bolster window of a side frame, the heads of rivets 50 project into openings formed in the tension member 12 and serve to properly lock the package unit in the side frame and to prevent accidental

movement of the package unit relative to the side frame of the truck.

It will be apparent from the foregoing that a novel package unit stabilizer is provided which is readily adapted for installation in railway car trucks of conventional construction, the said stabilizer unit providing progressively increased frictional pressure to increase the damping action in relation to the compression of the load springs.

I claim:

A package stabilizer unit adapted to be interposed between a truck bolster and a side frame of the truck comprising, in combination, upper and lower spring plates, a plurality of load supporting springs arranged between said plates, a casing open at the top and supported on said lower spring plates, said casing having opposed vertical friction surfaces and having vertical slots in opposed walls thereof, a friction wedge engageable with each of said friction surfaces, a central wedge depending from said upper spring plate and adapted to cooperate with said friction wedges to effect lateral movement thereof against said friction surfaces, a stabilizer spring associated with each of said friction wedges and adapted to urge said friction wedges upwardly against said central wedge and into frictional engagement with said friction surfaces, a loop depending from said central wedge and arranged substantially in alignment with said slots and a pin extending through said loop and said slot and adapted to maintain said stabilizing spring in partially compressed condition and to limit the movement of said plates in a direction away from each other.

CHARLES P. LEESE.
